UNITED STATES PATENT OFFICE.

OTTO HEINIGKE, OF NEW Utrecht, NEW YORK, ASSIGNOR TO THE HARTFORD CARPET COMPANY, OF HARTFORD, CONNECTICUT.

DESIGN FOR A CARPET.

SPECIFICATION forming part of Design No. 17,250, dated April 12, 1887.

Application filed February 18, 1887. Serial No. 228,123. Term of patent 3½ years.

To all whom it may concern:

Be it known that I, OTTO HEINIGKE, of New Utrecht, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

The figure A itself has a general oval shape 15 and conventional Greek-letter structure, and is repeated as shown. The ground is of damask-work or diaper-work made of any small geometric figures, as shown.

What I claim as new, and desire to secure 20 by Letters Patent, is—

The design for carpets, consisting of the figures A and the damask ground, substantially as shown and described.

OTTO HEINIGKE.
